CLAIM

The ornamental design for a tap handle, as shown and described.

DESCRIPTION

FIG. 1 is a perspective view of a tap handle, showing my new design;

FIG. 2 is a top plan view thereof;

FIG. 3 is a front side elevational view thereof, the back side being a mirror image; and,

FIG. 4 is a bottom plan view thereof.

The broken lines in FIG. 4 are for illustrative purposes only and form no part of the claimed design.
